BOAT HULL

Thomas P. Daniels, Royal Oak, Mich., assignor to
Seasafe Corporation, Birmingham, Mich.

Filed Jan. 13, 1970, Ser. No. 20,904

Term of patent 14 years

Int. Cl. D12—06

U.S. Cl. D71—1

FIG. 1 is a side elevational view of the boat hull;
FIG. 2 is a top view of the boat hull of FIG. 1;
FIG. 3 is a bottom view of the boat hull of FIG. 1;
FIG. 4 is a front view of the boat hull of FIG. 1; and
FIG. 5 is a rear view of the boat hull of FIG. 1.

I claim:

The ornamental design for a boat hull, substantially as shown and described.
